LATCH

Louis H. Lehman, Philadelphia, Pa.

Application August 22, 1936, Serial No. 97,331

5 Claims. (Cl. 292—75)

This invention relates generally to improvements in a latch construction and more particularly to a latch device of simple and inexpensive construction adapted for use in connection with

5 swingably mounted doors, windows and the like.

Among the principal objects of the present invention is to provide a latch in which a spring-pressed bolt or detent partakes of a combined sliding and rotating movement within its supporting casing in the course of its latching operation so as to reduce to a minimum friction which might tend to cause the bolt or detent to jam and so render the latch difficult to operate, if not wholly inoperative.

10 15 A further object of the present invention is to provide a latch construction in which the detent or bolt presents similar surfaces to the jamb element against which the latch-equipped closure abuts during the operations of closing and opening the closure, these surfaces being rounded and the detent being so arranged that a simple pressure on the closure in either opening or closing direction will effect the necessary retraction of the detent during engagement and disengagement thereof with respect to the jamb.

Still another object of the invention is to provide a latch unit which functions to securely retain a closure equipped therewith in closed position against a jamb, at the same time permitting the closure to be readily swung into open position and away from the jamb by simply pulling or pushing against the closure, thereby eliminating the necessity of employing in the latch unit any manually operable means for retracting the detent whenever the latter action is required.

Other objects and advantages of the invention will appear more fully hereinafter, it being understood that the invention consists substantially in the combination, construction, location and relative arrangement of parts, as described in detail hereinafter, as shown in the accompanying drawing, and as finally pointed out in the appended claims. In the accompanying drawing, it will be observed that the latch as constructed in accordance with and embodying the principles of the present invention is shown mounted upon a shower stall door. It will be understood that this showing is for illustrative purposes solely because obviously the latch unit of the present invention may be employed in connection with closures and devices other than that illustrated in the drawing. Moreover, it will be understood that the device of the present invention may function not only as a latch or detent to retain in closed position a swingably mounted closure, but it also may

be employed as an anti-rattling device to prevent rattling of windows and the like within their supporting frames.

In the said accompanying drawing:

Figure 1 is a front elevational view of a swingably mounted shower stall door equipped with a latch device constructed in accordance with and embodying the present invention;

Figure 2 is a horizontal sectional view taken on the line 2—2 of Figure 1;

Figure 3 is a longitudinal sectional view of the latch unit per se;

Figure 4 is a view showing in perspective the separate component part of the latch unit of the present invention;

Figure 5 is a horizontal sectional view corresponding to Figure 2 but showing a modified latching arrangement;

Figure 6 is a view showing a modified arrangement and installation of a latch constructed in accordance with the present invention; and

Figures 7 and 8 are sectional views showing still another modified form of the latch unit.

Referring now to the drawing and more particularly to Figures 3 and 4 thereof, it will be noted that the latch unit of the present invention comprises a body 18 preferably formed in one piece as by casting the same or stamping it of sheet metal. This body is in the form of a shell or casing 11 all sides of which are closed except for the front 12 thereof. Projecting oppositely from either side of the casing 11 are a pair of apertured securing lugs 13—13, the apertures 14—14 thereof being preferably in the form of elongated slots. The front edges of the supporting lugs 13—13 extend preferably coincidentally with the front edge of the casing 11, while the lugs themselves are preferably disposed in the plane of the base wall 15 of the casing.

Adapted to extend transversely between the opposed side walls 16—16 of the casing is a pin 17, the opposite extremities of this pin being respectively received within suitable apertures 18—18 provided in said side walls of the casing. As appears quite clearly in Figures 3 and 4, this pin 17 is located closely adjacent the open end of the casing and is adapted to retain in position a detent 19 of hollow cylindrical form. This detent 19 is of an external diameter slightly less than the internal depth of the casing 11 and is of an axial dimension slightly less than the width of said casing. The detent 19 is, therefore, adapted to be freely accommodated within the interior of the casing 11 and it is secured therein against accidental displacement therefrom by means of

the pin 17 which projects through the bore of the detent 19, as is most clearly shown in Figure 3. A coiled spring 20 is disposed interiorly of the casing 11 with the end thereof abutting the rear wall 21 of the casing and the front extremity thereof in engagement with the detent 19. This coil spring 20 thus functions to press the cylindrical detent 19 outwardly of the casing 11 to the maximum extent permitted by the transverse pin 17. When the detent is pressed outwardly to its maximum extent, as shown in Figure 3, it will be observed that the surface which extends exteriorly of the casing is substantially semi-cylindrical, thus providing similar curved surfaces *a* and *b* to either side of the plane common to the offset axes of the detent 19 and the pin 17. In consequence of this, it will be understood that the detent may be forced interiorly of the casing 11 against the normal biasing action of the coil spring 20, that is, into the dotted line position shown in Figure 3, by exerting a pressure against either of said curved surfaces *a* or *b*.

Figures 1 and 2 show the application of the latch of the present invention to a shower stall door 22 which is swingably mounted within a suitable frame 23 having a vertically extending jamb 24. This jamb 24 is provided with a lateral extension 25 extending longitudinally of the jamb and providing an abutment for the free vertical edge of the door 22. The latch 10 is mounted upon the inner surface of the door frame at a convenient elevation and with the front edge of the latch casing spaced inwardly of the free vertical edge of the door just sufficient to clear the vertical abutment 25 when the door is swung into closed position. With the latch mounted in this position, it will be observed that as the door is swung into closed position, the detent 19 passes freely over the free edge of the jamb abutment 25 and assumes the position shown in Figure 2 in which the jamb abutment is disposed between the outwardly biased detent and the inner face of the door frame.

To facilitate opening and closing of the door, the latter is provided with inner and outer handles 26—27 which are immovably secured upon opposite faces of the door, these handles being employed for opening and closing the door. It will be apparent that neither of these handles is employed to operate the latch except indirectly through movement of the door and consequently the handles need not be located as shown. Engagement and disengagement of the detent with respect to the jamb is effected solely through movement of the door into opened or closed position, it being noted that the shifting of the detent relatively to the jamb abutment and into the dotted line position shown in Figure 3 is similarly effected irrespective of whether the detent traverses the jamb from front to rear thereof, as when the door is closed or, vice versa, as when the door is opened.

Due to the cylindrical shape of the detent 19 and the fact that it is of hollow construction, the amount of friction encountered by the detent as it passes over the jamb abutment edge is reduced to a veritable minimum as is the possibility of the detent jamming within its casing. Also, due to the fact that the detent 19 is capable of partaking of a rotating movement simultaneously as it is pressed interiorly of its casing, marring of the surface finish of the jamb edge over which the detent passes is substantially eliminated. And finally, while the detent serves most effectively to secure the door in closed position

against accidental or unintentional opening, the door nevertheless may be readily opened from within or without the shower stall and thus eliminate the possibility of the door becoming locked in closed position.

The latch of the present invention is of course adapted to various installations, being not at all limited to the particular installation shown in Figure 2 wherein the swingable closure abuts against a fixed jamb element with the detent 19 retaining it in such position. Thus, in Figure 5 the closure 26 is free to swing laterally to either side of the jamb member 27, this latter being provided with a depression or seat 28 adapted to receive the detent 19 of the latch 10 whereby to maintain the closure in the position shown. By simply moving the closure laterally to either side of the jamb member 27, the latch detent is unseated from its retaining depression, and conversely, when the closure is swung into the position shown the detent rides into its seat to retain the closure in that position.

Figure 6 shows an arrangement wherein a latch of the present invention is set into a conventional door 29 or other such swingably mounted closure. In this arrangement, the free edge of the door is provided with a socket 30 which serves substantially as the socketed casing 11 of the latch unit hereinbefore described. The latch is provided with a detent 31 similar to that shown in Figures 1 to 5, which is, however, retained in position by means modified somewhat from that heretofore shown and described. This means includes a plate 32 which is inserted in the socket formed in the door edge and which is provided with a detent retaining element 33 formed either as an integral part of the plate or as a pin separately secured thereto. The element 33 if desired, may be struck out of the body portion 34 of the plate 32.

The rear extremity of the plate 32 may be upturned, as to 35, to provide a rear backing for the coil spring 36, while the front extremity of the plate is downturned to provide an anchorage to secure the plate permanently in position, as by means of a screw 37. If desired, the spring 36 may be provided with a follower cap 38, which may likewise be employed in the form of latch shown in Figures 1 to 5 inclusive.

It will be apparent, of course, that in all installations of the latch, the axis of the detent (19 of Figure 4 and 31 of Figure 6) parallels the edge of the closure upon which it is mounted. In some instances it may be desired that the detent be free to oscillate universally to a limited extent, that is, about an axis other than the detent axis. To this end, the edges of the detent may be rounded, as at 39, (see Figure 6), instead of being finished flat as shown in Figure 4.

Figures 7 and 8 show a slightly modified form of the latch unit constructed in accordance with and embodying the principal features of the present invention. In this modified form, the casing 40 may be stamped or drawn out of relatively thin metal, with the open end thereof outwardly flanged, as at 41. Struck out of the wall of the casing 40 immediately to the rear of the flange 41 are a pair of diametrically or oppositely disposed detent-limiting elements 42—42. These elements 42—42 project interiorly of the casing 40 and into the bore of the detent 43 to serve the same function as the pin 17 of Figure 3 and the element 33 of Figure 6. In all respects the latch unit of Figures 7 and 8 is

substantially like those above described, although it may be noted that if desired and to facilitate its insertion within a bored recess provided in the edge of a door or the like, the rear portion 5 of the casing 40 may be cylindrically formed, this being the portion which encompasses the coil spring 44 and its follower cap 45.

It will be understood, of course, that the invention is susceptible of various other changes 10 than those shown herein which may be made from time to time without departing from the essential principles thereof as defined in the appended claims. Thus, instead of employing a tubular detent of the nature shown, the detent 15 may be of substantially spherical shape with a diametrical bore therein of a diameter sufficiently greater than the diameter of retaining pin as to permit the rotating and sliding movement described as inherent in the detent shown in the 20 drawing, the latch casing being designed to snugly accommodate the modified detent.

What is claimed as new and useful is:

1. A latch of the character described comprising a main body member having an elongated 25 socket therein of rectangular cross-section, a tubular detent disposed within the mouth of said socket, means projecting transversely of the opposite walls of the socket and into the bore of said detent to limit the movement of the latter 30 within said socket, said means being operative to restrict the movement of the detent to an extent sufficient to present only a minor segmental portion thereof exteriorly of the socket, and spring-biasing means for urging said detent 35 outwardly of the socket to the extent permitted by said limiting means.

2. A latch of the character described comprising a main body member having an elongated 40 socket therein of rectangular cross-section, a hollow detent disposed within the mouth of said socket and with the axis of the bore thereof extending transversely of the socket, means for limiting the movement of said detent, said means being carried by the socket walls for projection 45 into the bore of the detent and being operative to restrict the movement of the detent to an extent sufficient to present only a minor segmental portion thereof exteriorly of the socket, and means for biasing said detent to normally 50 maintain it partially projected from said socket.

3. A latch of the character described comprising a main body member having an elongated 55 socket therein of rectangular cross-section, a

hollow detent disposed within the mouth of said socket and with the axis of the bore thereof extending transversely of the socket, means projecting interiorly of the socket and into the bore of the detent to retain the latter against displacement from its socket, said means being operative to restrict the movement of the detent to an extent sufficient to present only a minor segmental portion thereof exteriorly of the socket, and means for biasing said detent to normally 10 maintain it partially projected from said socket, the relative arrangement of the detent and its retaining means being such as to permit the detent to partake of a combined rotative and rectilinear shifting movement relatively to said retaining means. 15

4. A latch of the character described comprising a socketed main body member having substantially parallel side walls, a pin extending transversely across the socket adjacent the open 20 end thereof, and a spring-pressed tubular detent loosely embracing said pin and adapted normally to project exteriorly of said socket, said pin being operative to permit only a minor segment of the detent to project exteriorly of the 25 socket, the bore of the detent being of a diameter sufficiently great relatively to that of said pin as to permit it to be bodily shifted interiorly of the said socket, the side walls of the socket 30 serving as guides for the detent throughout its shifting movement.

5. A latch of the character described comprising a socketed main body member having substantially parallel side walls, a pin extending transversely of the socket adjacent the open end 35 thereof, a cylindrical detent disposed within the socket in loosely embracing relation with respect to said pin, the latter being disposed a sufficient distance inwardly of the open end of the socket to so limit the outward shifting of the 40 detent that the axis thereof does not traverse the plane of the open end of the socket, and means for exerting an outwardly directed bias upon the detent whereby only a minor segmental portion thereof normally projects exteriorly of 45 said socket, the bore of the detent being of a diameter sufficiently great relatively to that of said pin as to permit it to be bodily shifted interiorly of the said socket, the side walls of the socket 50 serving as guides for the detent throughout its shifting movement.

LOUIS H. LEHMAN.
